UNITED STATES PATENT OFFICE

HERMAN L. KRAEFT, OF CLEVELAND, OHIO, ASSIGNOR TO MURRAY OHIO MANUFACTURING COMPANY, OF CLEVELAND, OHIO, A CORPORATION OF OHIO

WHEELED TOY

Application filed February 24, 1930. Serial No. 430,783.

The object of this invention is to provide an improved toy construction, of the type having a smoke stack, or stack simulating device thereon. A large number of toys; for example, toy replicas of steam rollers, locomotives, tractors and the like have vertical tubes representing smoke stacks. The toy illustrated herewith is a steam roller, with the stack at the front end, and the essential 5 feature is that the steering arrangement is combined with the stack, in such manner that it does not detract from the appearance of the stack as such, while at the same time it is advantageously located for steering.

Further objects and features of the invention will become apparent from the following description relating to the accompanying drawings showing the preferred form. The essential novel features are summarized in 10 the claims.

In the drawings, Fig. 1 is a side elevation of a toy steam roller incorporating my invention; Fig. 2 is a substantially central longitudinal sectional view of the toy; Fig. 3 is 15 a fragmentary cross sectional plan view taken along the line 3—3 of Fig. 2; Fig. 4 is a fragmentary transverse cross sectional view as indicated by the line 4—4 on Fig. 2, and Fig. 5 is a view similar to Fig. 3 with the steering 20 parts in a different relationship.

Referring in detail to the drawings, 1 indicates a suitable main body or frame. This preferably comprises suitably shaped sections of sheet metal, there being a top portion 3 25 and side portions 4 rigidly joined in any suitable manner. Surmounting the body is a cab structure including upright frame members 5 for supporting a transversely crowned top or roof 6. Ahead of the cab and extending 30 out of the top of the body is a hollow tube 7 forming the stack. If desired, the cab may be provided with side closure members 9 and these may carry a shaft 10 supporting wheels 10' exteriorly of the cab to represent, for 35 example, the fly-wheels of an engine.

The toy has a pair of large rear wheels 15 on an axle 16, supported by and extending through the side members 4, and a dirigible 40 relatively small front wheel 17. All these 50 wheels preferably have relatively wide treads

as in the usual full sized steam roller construction.

At its forward end, the body is undercut, as at 11, to clear the front wheel 17, the latter being supported on a fork 18 which is in turn 55 carried by a vertical pivot or king pin 19. The king pin, as shown, extends through the body top portion and a cross brace 20 connecting the body sides. The king pin may have a suitable head 19 to hold the fork 60 against vertical movement, and the pin itself may be held in place by a cotter pin 23 above the top of the body.

For swinging the front wheel 17, to thereby steer the toy, the fork 18 has a rearwardly 65 extending steering arm 25 centrally of the toy and within the body 1. Cooperating with this arm is a steering shaft 28 mounted within and laterally supported by the stack 7. Preferably, the stack is held in place by an in-turned tubular portion 31 of the body which is telescoped by the lower end of the stack and to which the latter may be spot welded or otherwise rigidly fixed. A lower bearing 70 for the shaft 28 may comprise a cross plate 75 33, secured as by bolts 34 to the underside of the body, as shown in Fig. 4.

The bottom end of the shaft is bent, as at 35, to form an arm, the free depending end 35' of which extends through a slot 36 in the steering arm 25; the arrangement being such that turning the shaft will thereby turn the fork and front wheel. The upper end of the shaft 28 carries a steering wheel 38, shown 80 as a pressed metal cap rigid with the shaft 85 and having a depressed central portion 39 fitting into the top of the stack to hold the shaft in position. The outer rim of the cap is turned into a bead 40 to provide a hand hold for the child. Suitable means for holding the shaft against upward movement may comprise nibs 41 struck out in the usual manner from the shaft just below the cross plate 33.

In order to guide and assist in supporting the wheel 17, the fork 18 may be provided with a bail-like member 50 which, as shown, is rigidly fastened at its forward ends to the depending arms of the fork 18. Rearwardly 90 from this, the bail has an arcuate portion 51, 100

the arc being determined by the location of the king pin. As the fork is turned, this arcuate portion of the bail moves freely in a guide 52 depending from a cross brace 53, secured as by flanges to the sides 4 of the body.

5 It will be seen from the above description, that I have provided a toy in which the usual smoke stack simulating member supports or embodies one of the essential parts of the steering device. I believe this is an entirely 10 new thought in toy construction. It is obvious that various modifications may be made in the steering arrangement, and that any of the wheels of this or similar toys may be 15 steered rather than a central front wheel, by dirigibly mounting such other wheels and providing suitable link connections therefrom to a steering shaft or column associated with or made part of the stack.

20 If desired, instead of a separate shaft running down through the stack for connection with the steering mechanism, I may mount the stack itself in such manner that it may turn and thereby effect steering. This is not 25 illustrated.

I claim:

1. A toy construction including supporting wheels, one of which wheels is adapted to be turned to steer the toy, a smoke stack simulating device on the toy, and steering means 30 connected to said turnable wheel and associated with the stack.
2. In a toy, a body, supporting wheels carried by the body, one of said wheels being 35 turnable on a vertical axis to steer the toy, a tube surmounting the body and simulating a smoke stack, a shaft extending through the tube, means on the shaft surmounting the stack, whereby the shaft may be turned by 40 a child using the toy, and means operatively connecting the shaft with the said turnable wheel.
3. In a toy steam roller, a body, a pair of rear non-dirigible wheels having a relatively 45 wide tread, a centrally disposed dirigible wheel also having a relatively wide tread and disposed beneath the body, a smoke stack simulating tube surmounting the body at the front end thereof, a steering shaft passing through said tube and supported thereby, and means operatively connecting the shaft 50 to said dirigible wheel.

In testimony whereof, I hereunto affix my signature.

55 HERMAN L. KRAEFT.
